(57) **CLAIM**

I claim the ornamental design for an active cover plate, as shown and described.

DESCRIPTION

FIG. 1 is a left front isometric view of an active cover plate showing my new design;

FIG. 2 is a front elevational view thereof;

FIG. 3 is a right-side elevational view thereof;

FIG. 4 is a rear elevational view thereof;

FIG. 5 is a left-side elevational view thereof;

FIG. 6 is a bottom plan view thereof; and,

FIG. 7 is a top plan view thereof.

The broken line showing in FIG. 4 is included for the purpose of illustrating a rear portion of the active cover plate and forms no part of the claimed design.
